UNITED STATES PATENT OFFICE

2,328,913

SUPPORT RACK FOR CARTONS OF BOTTLES OR THE LIKE

Charles H. Kruea, Fort Thomas, Ky., assignor of one-half to Edwin H. Creutz, Fort Thomas, Ky.

Application July 17, 1941; Serial No. 402,813

3 Claims.

(Cl. 211—74)

This invention relates to racks or stands of the type adapted to rest on the floor and to support, for storage and display purposes, cartons or bags of bottles or the like.

As is well known in the industry, the present custom is to supply bottled soft drinks in cartons or bags; that is, to sell them as units of one-half a dozen in a carton. These cartons include hand-hold portions or elements for ease in carrying them. Also, the cartons or packages carry appropriate advertising for the bottled product.

It has been an object of the present inventor to provide a display rack or stand providing support means for supporting a multiplicity of these cartons or bags in positions wherein the merchandise is displayed and the advertising on the cartons is fully visible.

It has been a still further object of the present inventor to provide a rack of this type which provides mounting means for the cartons cooperating with the conventional hand-hold portions or handles of the cartons or bags for suspending the cartons or bags in positions from which they can be easily removed and upon which they can be easily hung.

It has been a still further object of the present inventor to provide an arrangement of the supporting mediums whereby the capacity of the rack is considerable; that is, wherein rows of cartons may be supported with the back rows visible to anyone standing before the rack and wherein the structure of the rack is sturdy and capable of supporting the combined weight of a great many cartons of bottles.

Other objects and certain advantages of the invention will be more fully apparent from the description of the drawing in which:

Figure 1 is a front view of a rack embodying the present invention.

Figure 2 is a side view of the rack.

Figure 3 is a top plan view of the rack.

Figure 4 is a fragmentary sectional view taken on line 4—4, Figure 1.

Figure 5 is a fragmentary perspective view showing a modified, adjustable hanger hook.

Figure 6 is a sectional view taken on line 6—6, Figure 5.

The stands or racks of this invention are designed to support, for storage and display, cartons or bags of bottles. These cartons or bags are of the type adapted to carry six bottles. It is the customary practice to sell soft drinks in lots of six and to provide them in cartons or bags for convenience in carrying the bottles be-

19, thus, provides a rigid joint when the arm is riveted in place.

The feet 13 may be made from angle irons and they extend forwardly from the lower ends of the uprights. An angle iron brace 20 is provided from each foot. The brace 20 is fixed respectively to the forward end of each foot and to the upright. At the back of the rack the pair of diagonal braces 14 cross each other and are fixed to respective sides of the rack at the tops and bottoms of the T-iron uprights.

At the tops of the uprights clips 21 may be provided for holding an advertising or display sign. Each clip is constituted by two spring leaves which are riveted together medially of their lengths. In the upper half, the leaves are bowed from one another and meet at the upper ends for gripping the sign. At the lower end of each clip the leaves engage over the inner flange of the T-iron upright and are fixed thereto.

In Figures 5 and 6 a modified form of the hanger hooks is shown. Here, the hooks are part of a slideable element 23 which is adjustable longitudinally of the rack. The element is mounted on an angle iron hanger bar 24 which is joined to the support arms 11 by a bracket 25 riveted to the arms and the bar respectively. The angle iron is positioned with the one flange 26 extending horizontally toward the front, and the other flange 27 extending vertically up from the back edge thereof. The element 23 is formed from sheet metal and is configurated to correspond to the shape of the angle iron bar. The hooks 29-30 and hand notch 30 are at the front edge of the element. The top face of the element slants up from the hooks over the angle iron hanger bar, passes down around the back of the angle iron, then under it toward the front and is hooked up around the front edge of the flange 26 as at 28.

It will be noted from Figure 6 that when a weight is hung on the hanger hooks of the element, the hook portion at 28 is pulled tightly against the flange 26 of the angle iron hanger bar. Thus, the hanger bar is gripped by the element and held against accidental movement along the bar. Accordingly, with the weight removed, the element is free to be moved for adjusting its position on the bar 24.

The inclined arms permit better display of the cartons. In other words, those on the rear bars may be seen from the front and the full use of the advertising is accomplished. Moreover, the arms are stronger; that is, a better leverage for resisting the weight of the cartons is achieved, and the entire structure is more rigid.

Having described my invention, I claim:

1. A support rack for cartons of the type having elongated hand-hold openings, comprising, a frame providing vertical members, horizontally disposed support bars mounted on said vertical members in vertically spaced relationship, said bars in each instance being formed of angle iron strips, suspending means comprising pairs of fixedly spaced hook members extending out beyond the outer longitudinal edge of one flange of each angle iron strip, the material between the spaced hooks of each pair being notched out to provide clearance for the fingers when the cartons are being lifted from suspended positions on the hooks.

2. A support rack for cartons of the type having elongated hand-hold openings, comprising, a frame providing vertical members, horizontally disposed support bars mounted on said vertical members in vertically spaced relationship, said support bars being formed of angle iron strips with horizontal and vertical flanges, one flange of each strip including pairs of fixedly spaced hook members extending from the outer longitudinal edge, the flange being notched out between the hooks of the respective pairs for providing clearance for the fingers when the cartons are being lifted from suspended positions on the hooks.

3. A support rack for cartons of the type having elongated hand-hold openings, comprising, a frame, a horizontally disposed bar mounted on said frame, hook elements slidably mounted on said bar, each hook element including a reversely bent end engaged over one end of said bar and a portion extending around the bar with a supporting portion projected outwardly over and beyond the flange end and including spaced hook members having a clearance space therebetween for removal of the cartons supported on the hooks.

CHARLES H. KRUEA.
